Primary Examiner — Karen E. Eldridge Powers*Assistant Examiner* — Kimberly Barnes(74) *Attorney, Agent, or Firm* — Sheridan Ross P.C.(57) **CLAIM**

The ornamental design for headgear, as shown and described.

DESCRIPTION

FIG. 1 is a perspective view of the headgear showing the new design;
FIG. 2 is a front elevation view thereof;

FIG. 3 is a rear elevation view thereof;

FIG. 4 is a right elevation view thereof;

FIG. 5 is a left elevation view thereof;

FIG. 6 is a top plan view thereof;

FIG. 7 is a bottom plan view thereof; and,

FIG. 8 is a front elevation view of the headgear shown in a flat, preassembled position of use.

The broken line shown in FIG. 8 illustrates a line of perforation which forms part of the claimed design.
